UNITED STATES PATENT OFFICE.

GLENN ARNOLD HOWE, OF PORTLAND, OREGON.

INDICATING-VALVE.

1,297,851.

Specification of Letters Patent. Patented Mar. 18, 1919.

Application filed August 8, 1917. Serial No. 185,054.

To all whom it may concern:

Be it known that I, GLENN ARNOLD HOWE, a citizen of the United States, and a resident of Portland, in the county of Multnomah and State of Oregon, have invented new and useful Improvements in Indicating-Valves, of which the following is a specification.

My invention is an improvement in indicating valves, and has for its object to provide a valve adapted for use in pneumatic tires, wherein indicating mechanism is provided, designed to show the pressure existing in the interior of the tire, and without 10 the necessity for uncoupling the pump or air connection to ascertain such pressure.

In the drawings:

Figure 1 is a longitudinal section of the improved valve;

Fig. 2 is a front view of the upper portion of the valve;

Fig. 3 is a section on the line 3—3 of Fig. 1.

In the present embodiment of the invention, the valve casing 1 is of the usual construction, having the flange 2 at its inner end and the clamping nut 3 and the rim washer 4 for clamping the tube 5 between the flange and the said washer and nut, the 30 nut being threaded on to the casing.

The casing, in the present instance, is externally threaded throughout its length and a dust cap 6 has threaded engagement with the outer end of the stem. The cap, as 35 shown, has oppositely arranged sight openings 7 for permitting the tubular member 8 to be visible through the said sight openings. This tubular member 8 is movable in the body or casing, the extent of movement being, however, limited by a set screw 9 which is threaded through the casing and which engages a longitudinally extending groove 10 in the tubular member.

An elastic sleeve 11 is arranged within the 45 body, the inner end of the tubular member 8 being recessed or counterbored, as indicated at 12, and the adjacent end of the sleeve 11 is held in place in the tubular member 8 by means of a hollow screw 13.

The opposite end of the sleeve 11 is connected to the base pin 14 by means of a hollow screw 15, the inner end of the base pin having a head 16 which is counterbored to receive the end of the sleeve 11. Thus the 55 tubular member 8 is connected to the base pin by the elastic sleeve. A coil spring 17

encircles the sleeve 11, being rigidly connected at one end to the tubular member and at the other to the head 16 of the base pin. This spring normally holds the parts in the position of Fig. 1, but they may yield at a predetermined pressure to permit the tubular member 8 to move outwardly. As soon as this pressure is relieved the spring returns the parts to normal position. It will be noticed that the tubular member 8 is provided with scales 18 with which the outer end of the valve casing co-operates as an indicator.

In use, the tire is inflated, the tubular member 8 being gradually moved outward, and this movement is not interfered with by the elastic sleeve, and as the numerals of the scale pass the outer end of the tubular member 8 these numerals will become visible in succession, showing the pressure in the tire, it being understood that the scale is based on the strength of the spring.

I claim:

1. A self registering inflation valve comprising a stem having co-axial large and small bores, the latter located adjacent to its inner end and the former extending from its outer end for the major portion of its length, a hollow base pin interfitting the small bore, a tubular member slidably interfitting the outer end of the large bore and having an external scale co-operating with the outer end of the stem, a valve within said tubular member, and a hollow flexible sleeve connecting the adjacent ends of said tubular member and said base pin within the stem, said base pin having a connecting member externally of the inner end of the stem, whereby the flexibly connected base pin and tubular member as a whole may be inserted in, and removed from, the stem.

2. A self-registering inflation valve comprising a stem having co-axial large and small bores, the latter located adjacent to its inner end and the former extending from its outer end for the major portion of its length, a hollow base pin interfitting the small bore and extending through the small bore and connected to the inner end of the stem, a tubular member slidably interfitting the outer end of the large bore and having an external scale co-operating with the outer end of the stem, a valve within said tubular member, and a hollow flexible sleeve connecting the adjacent ends of said tubular member and said base pin within the stem,

said tubular member having a longitudinal groove, and a set screw threaded through the wall of the stem and extending at its inner end into said groove, to detachably connect the tubular member movably within its limits in the stem and prevent turning movements of the said member with respect to the stem.

3. A self-registering inflation valve comprising a hollow stem, a tubular member slidably interfitting the outer portion of the hollow of said stem and having an external scale coöperating with the outer end of the stem, an air valve within said tubular mem-

ber, a hollow base pin detachably connected 15 with the inner portion of the stem and having its inner end opposing the inner end of the tubular member, said base pin and said tubular member having their said opposing ends counter-bored and internally threaded, 20 a flexible sleeve having its opposite ends extending into said counter-bores, and hollow screws threaded into the adjacent ends of the tubular member and the base pin to lock the said ends of the said sleeve in the counter-bores. 25

GLENN ARNOLD HOWE.
